UNITED STATES PATENT OFFICE.

AUGUST BLOMQUIST, OF CHICAGO, ILLINOIS.

HOT-WATER ATTACHMENT FOR GAS-STOVES.

1,160,246.

Specification of Letters Patent.

Patented Nov. 16, 1915.

Application filed July 1, 1915. Serial No. 37,486.

To all whom it may concern:

Be it known that I, AUGUST BLOMQUIST, a subject of the Czar of Russia, and a resident of the city of Chicago, county of Cook, and 5 State of Illinois, have invented certain new and useful Improvements in Hot-Water Attachments for Gas-Stoves, of which the following is a specification.

My invention relates to improvements in 10 hot water attachments for gas stoves, and has for its object the provision of an improved construction of this character which is simple and efficient in use.

The invention consists in the combinations 15 and arrangements of parts hereinafter described and claimed.

The invention will be best understood by reference to the accompanying drawing forming a part of this specification, and in 20 which,

Figure 1 is a top plan view of a burner-attachment embodying the invention, and Fig. 2, a vertical section taken on line 2—2 of Fig. 1.

25 The preferred form of construction, as illustrated in the drawing, comprises an annular gas chamber 3 provided with any usual or desirable form of gas supply valve 4 for supplying a combustible mixture thereto.

30 The top of chamber 3 is provided with a substantially annular opening positioned centrally therein and a similarly shaped water pipe 5 is seated in said opening. Burner openings 6 are provided in the top of chamber 3 on each side of pipe 5, and the usual spider or cooking utensil support 7 is arranged above the burner thus provided.

35 By this arrangement a simple and effective hot water heating-attachment is pro-

vided for gas stoves, and one in which ample 40 room for spreading of the flame and perfect combustion is provided under the bottom of utensils on the top of the supporting frame.

While I have illustrated and described the preferred form of construction for carrying 45 my invention into effect, this is capable of variation and modification without departing from the spirit of the invention. I, therefore, do not wish to be limited to the precise details of construction set forth, but 50 desire to avail myself of such variations and modifications as come within the scope of the appended claims.

Having described my invention what I claim as new and desire to secure by Letters 55 Patent is:

1. A construction of the class described comprising a gas supply chamber having an opening at its top and burner openings at each side thereof; and a water pipe seated 60 in and closing said opening and extending partially into said chamber, substantially as described.

2. A construction of the class described comprising an annular gas supply chamber 65 having an annular central opening in its top and burner openings at each side of said central opening; and a water pipe seated in and closing central opening and extending partially into said chamber, substantially as 70 described.

In testimony whereof I have signed my name to this specification in the presence of two subscribing witnesses.

AUGUST BLOMQUIST.
